FIREARM SAFETY

Martin Kelly Clifton, Vesta, Va., assignor of one-fourth to Russell B. Cassell

Application June 15, 1939, Serial No. 279,366

3 Claims. (Cl. 42—70)

The present invention relates to new and useful improvements in safety devices for automatic shot guns and other firearms of the single trigger type and has for one of its important objects to provide, in a manner as hereinafter set forth, a device of this character which moves automatically to operative or locking position without attention on the part of the person using the gun.

Another very important object of the invention is to provide an automatic safety of the aforementioned character which is adapted to be moved to inoperative or released position upon the insertion of a finger in the guard of the fire-arm for engagement with the trigger.

Still another very important object of the invention is to provide an automatic safety of the character described which is adapted to function as a shield for preventing the trigger from being struck by twigs, limbs, etc., and being actuated thereby thus accidentally discharging the gun.

Other objects of the invention are to provide an automatic safety for firearms which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view partially in vertical section and partially in side elevation, showing a fire-arm safety constructed in accordance with the present invention.

Figure 2 is a top plan view of the invention, showing it adapted to the plate of a Browning automatic shotgun.

Figure 3 is a top plan view of the lever and cam.

Figure 4 is a detail view in side elevation of the slideable latch.

Figure 5 is a detail view in top plan of the slideable latch.

Referring now to the drawing in detail, it will be seen that the reference numeral 1 designates a trigger guard which depends from the forward portion of a metallic plate 2. The plate 2 has formed longitudinally therein a slot 3 in which the trigger 4 is pivotally mounted, said trigger being operable in the guard 1. Formed in the

trigger 4 is a notch 5 the purpose of which will be presently set forth.

Mounted for longitudinal sliding movement in the forward portion of the slot 3 is a bolt or latch 6. The latch 6 has formed longitudinally in its sides grooves 7 which receive ribs 8 on the walls of the slot 3. Depending from the forward end portion of the latch 6 is a lug 9. The lug 9 is operable in an opening 10 which is provided therefor in the forward portion of the guard 1, 10 said opening communicating with the slot 3.

The rear end portion of the latch 6 is engageable in the notch 5 for locking the trigger 4. This is shown to advantage in Fig. 1 of the drawing. Rising from the rear end portion of the latch 15 6 is an ear 11 having an opening 12 therein. The opening 12 accommodates a pin 13 which is mounted in the plate 2 in the forward portion of the slot 3. A coil spring 14 on the pin 13 is engaged with the ear 11 for yieldingly urging 20 the latch 6 toward the trigger 4.

Threadedly mounted for adjustment in the plate 2 and the forward portion of the trigger guard 1 are aligned bearings 15. The reference numeral 16 designates a lever in the form of a 25 metallic plate having vertical pintles 17 on its forward end journaled in the bearings 15. Thus, the lever 16 is mounted for swinging movement in a horizontal plane in the guard 1 forwardly of the trigger 4.

The latch 6 has formed longitudinally therein a slot 18 which accommodates the upper bearing 15. Fixed on the uppermost pintle 17 is a cam 19 which is adapted to actuate the latch 6 to inoperative position against the tension of 35 the coil spring 14.

It is thought that the operation of the device will be readily apparent from a consideration of the foregoing. With the latch 6 engaged in the notch 5 of the trigger 4 under the influence 40 of the coil spring 14, said trigger is positively locked. When a finger is inserted in the guard 1 from either side for engagement with the trigger 4 the lever 16 is swung laterally thereby rotating the cam 19. As the cam 19 is engaged 45 with the lug 9 the latch 6 is moved forwardly against the tension of the coil spring 14 out of the notch 5 thereby releasing the trigger 4. When the lever 16 is released said lever is immediately returned to operative position in longitudinal 50 alignment with the trigger 4 by the coil spring 14 through the medium of the latch 6, the lug 9 and the cam 19. Thus, the lever 16 functions as a shield for preventing the trigger 4 from fouling on twigs, bushes, etc. It will also be 55

observed that the latch 6 immediately returns to locking position in engagement with the trigger 4 when the lever 16 is released. By adjusting the threadedly mounted bearings 15 the frictional resistance of the lever 16 to swinging movement may be regulated as desired. The construction and arrangement also is such that engagement of the finger with the trigger for pressing said trigger will be virtually impossible without first actuating the lever 16. The reference numeral 20 designates a return spring for the trigger 4.

It is believed that the many advantages of a firearm safety constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. A firearm comprising a trigger, a latch slidably mounted on the firearm and engageable with the trigger for locking same, resilient means for actuating the latch to operative position, a lever pivotally mounted on the firearm, and a cam on said lever operatively engaged with the latch for disengaging said latch from the trigger.

2. A firearm safety comprising a slidably mounted latch engageable with the trigger of the firearm for locking said trigger, a lug depending from said latch, an ear rising from the latch, a coil spring engaged with the ear for actuating the latch toward operative position, a lever pivotally mounted on the firearm forwardly of the trigger, and a cam on the pivoted end of the lever operatively engaged with the lug for retracting the latch against the tension of the coil spring.

3. In a firearm including a plate having a longitudinal slot therein and a trigger guard depending from the plate, a trigger pivotally mounted in the slot and operable in the guard, said trigger having a notch therein, a latch slidably mounted in the slot and engageable in the notch for locking the trigger, a lug depending from the latch, vertically aligned, adjustable bearings threadedly mounted in the plate and guard, a lever including vertically aligned pintles on one end journaled in said bearings, said lever being operable in the guard forwardly of the trigger, a cam on the pivoted end of the lever engaged with the lug for retracting the latch, and a spring operatively engaged with the latch for engaging said latch with the trigger.

MARTIN KELLY CLIFTON.
